DESIGN FOR A MATTRESS

Joseph Martin, Laurelton, N. Y., assignor to United States Cabinet Bed Co., Brooklyn, N. Y., a corporation of New York

Application February 8, 1944, Serial No. 112,512

Term of patent 14 years

(Cl. D5—2)

To all whom it may concern:

Be it known that I, Joseph Martin, a citizen of the Republic of Spain and resident of Laurelton, in the county of Queens and State of New York, have invented a new, original, and ornamental Design for Mattresses, of which the following is a specification, reference being had to the accompanying drawing, forming part thereof.

In the drawing:

I claim:

The ornamental design for a mattress, as shown.

JOSEPH MARTIN.
